UNITED STATES PATENT OFFICE

KARL JOHAN SVENSSON, OF ALSTEN, SWEDEN, ASSIGNOR TO THE DE LAVAL SEPARATOR COMPANY, OF NEW YORK, N. Y., A CORPORATION OF NEW JERSEY

CENTRIFUGAL SEPARATOR

Application filed October 15, 1929, Serial No. 399,758, and in Sweden November 3, 1928.

The present invention comprises the combination, with a separator bowl, of a frame provided with or carrying a fixed conduit for the liquid to be supplied to the separator, a fixed conduit for conveying away liquid discharged from the separator, a collecting vessel hinged to the frame or one of said conduits and provided with a supply channel and a discharge channel adapted, when the collecting vessel is closed, to register with the fixed supply conduit and fixed discharge conduit respectively, and means, operative at the interruption of the supply of liquid and the opening of the collecting vessel, to prevent the liquid remaining in said supply channel from streaming out of the channel and over the separator.

The accompanying drawing is a vertical sectional view of a centrifugal separating machine embodying the invention.

The centrifugal separator bowl *a* turns in bearings in a frame *b*, which is shaped to form a casing enclosing the lower part of the bowl.

Hinged at *c* is a collecting vessel comprising a cover *d*, a casing *e* enclosing the upper part of the bowl, and a conical pan *f* adapted to receive separated or purified liquid discharged from the bowl.

At one side of the frame *b* is supported a fixed conduit *g* adapted to carry away liquid discharged from the separator bowl onto the pan *f*. The collecting vessel carries a tube *h* communicating with the pan *f* and adapted, when the collecting vessel is swung down on its hinge *c* into a closed position, to register with the conduit *g*.

At the other side of the frame *b* is supported a fixed conduit *i* through which the supply liquid is conveyed upward, under pressure, into a feed channel carried by the collecting vessel. This feed channel comprises a passage *k* formed in the cover of the collecting vessel, a nozzle *m* which feeds the liquid direct into the separating space of the bowl *a*, and a tube *j* which, when the collecting vessel is closed, registers with the fixed conduit *i*.

When, in the operation of the machine, so far as it is above described, the supply is interrupted, a certain amount of liquid remains

in the supply channel. Without safeguarding means this liquid would stream out over the separator upon lifting the collecting vessel. This action, however, is avoided, in the construction embodying my invention, by the provision of an automatic valve in the feed channel. The valve structure is preferably located at the lower end of the tube *j*. It may have any suitable construction. As shown it comprises a valve seat *o*, a valve *p* whose stem is slideable in a support or guide *r* and a coil spring *s* surrounding the valve stem and confined between the guide *r* and the valve head.

The tension of the spring is such as to be readily compressible by the normal pressure in the feed line while liquid is being fed to the separator; but when that pressure is released, or drops below a predetermined limit, the valve automatically closes, thus preventing the escape of any liquid in the tube *j* when the collecting vessel is swung up into open position.

The described valve structure is particularly suitable when considerable pressure is available, as, for example, that produced by a pump. If the pressure is light, the valve may be arranged for manual operation and is closed before raising the cover.

Having now fully described my invention, what I claim and desire to protect by Letters Patent is:

1. The combination with a centrifugal separator bowl, of a liquid supply conduit whose outlet end opens upward, a collecting vessel in hinged relation with the supply conduit and provided with a feed channel whose inlet end is between the axis of its hinge and its opposite free end and which is adapted to register with the outlet end of the supply conduit when the collecting vessel is moved down into closed position and to recede from the outlet end of the supply conduit when the collecting vessel is moved up into open position, and a valve controlling the flow of liquid through the feed channel, said valve being carried wholly by the collecting vessel.

2. The combination with a centrifugal separator bowl, of a liquid supply conduit whose outlet end opens upward, a collecting vessel in hinged relation with the supply

conduit and provided with a feed channel whose inlet end is between the axis of its hinge and its opposite free end and which is adapted to register with the outlet end 5 of the supply conduit when the collecting vessel is moved down into closed position and to recede from the outlet end of the supply conduit when the collecting vessel is moved up into open position, and a normally 10 closed valve controlling the flow of liquid through the feed channel, the valve being carried by the collecting vessel and positioned at the inlet end of the feed channel and adapted to be opened, when the collecting vessel is lowered into closed position, by the pressure of the incoming feed liquid, and closing when the collecting vessel is lifted into open position.

3. The combination with a centrifugal separator bowl, of a liquid supply conduit whose outlet end opens upward, a collecting vessel in hinged relation with the supply conduit and provided with a feed channel whose inlet end is between the axis of its hinge and its 20 opposite free end and which is adapted to register with the outlet end of the supply conduit when the collecting vessel is moved down into closed position and to recede from the outlet end of the supply conduit when the 25 collecting vessel is moved up into open position, and a valve controlling the flow of liquid through the feed channel, the valve spring being actuated and thereby normally closed whether the collecting vessel is in open 30 or closed position and adapted to open against the force of its spring, only when the pressure of the supply liquid exceeds the spring pressure.

4. The combination with a centrifugal separator bowl, of a liquid supply conduit whose outlet end opens upward and a liquid discharge conduit whose inlet end opens upward, a collecting vessel provided with a feed channel and a discharge channel both 40 opening downward and adapted, when the collecting vessel is moved down into closed position, to cause the said channels to register respectively with the supply conduit and the discharge conduit and adapted, when the 45 collecting vessel is moved up into open position, to lift said channels away from their respective conduits, and a valve adapted to be opened during the feed of liquid to the bowl and to be closed when the collecting 50 vessel is moved into open position, said valve being carried by the collecting vessel and positioned at the inlet end of the feed channel.

In testimony of which invention, I have hereunto set my hand, at Stockholm, Sweden, 60 on this 1st day of October, 1929.

KARL JOHAN SVENSSON.
